(57) **CLAIM**

The ornamental design for a breathing tube for medical respiratory apparatus as shown and described.

DESCRIPTION

1.1 is a front side view of the breathing tube for medical respiratory apparatus.

1.2 is a back side view of the breathing tube for medical respiratory apparatus.

1.3 is a left view of the breathing tube for medical respiratory apparatus.

1.4 is a right view of the breathing tube for medical respiratory apparatus.

1.5 is a top view of the breathing tube for medical respiratory apparatus.

1.6 is a bottom view of the breathing tube for medical respiratory apparatus.

1.7 is a perspective view of the breathing tube for medical respirator apparatus.

1.8 is another perspective view of the breathing tube for medical respirator apparatus.

1.9 is another perspective view of the breathing tube for medical respirator apparatus.

1.10 is another perspective view of the breathing tube for medical respirator apparatus.

1.11 is another perspective view of the breathing tube for medical respirator apparatus.

The broken lines depict portions of the breathing tube for medical respiratory apparatus that form no part of the claimed design.

1 Claim, 11 Drawing Sheets
